UNITED STATES PATENT OFFICE.

PETER N. LANDINE, OF MILFORD, CONNECTICUT, ASSIGNOR TO THE ROSTAND MANUFACTURING COMPANY, OF MILFORD, CONNECTICUT, A CORPORATION OF CONNECTICUT.

DESIGN FOR AN ORNAMENTAL TUBING.

50,050.

Specification for Design.

Patented Dec. 12, 1916.

Application filed September 30, 1916. Serial No. 123,165. Term of patent 7 years.

To all whom it may concern:

Be it known that I, PETER N. LANDINE, a citizen of the United States, residing at Milford, New Haven county, State of Connecticut, have invented a new, original, and ornamental Design for Ornamental Tubing, of which the following is a specification, reference being had to the accompanying drawing, forming a part thereof.

In said drawing: Figure 1 is a perspective view of a piece of ornamental tubing embodying my invention. Fig. 2 is an end view of the same.

I claim—

The design for ornamental tubing as shown, or any imitation thereof.

PETER N. LANDINE.
